J. O. FUNKHOUSER.
COMBINATION STOP ACTION.
APPLICATION FILED MAR. 5, 1907.

2 SHEETS—SHEET 2.

UNITED STATES PATENT OFFICE.

JACOB O. FUNKHOUSER, OF HAGERSTOWN, MARYLAND.

COMBINATION STOP-ACTION.

No. 873,364.

Specification of Letters Patent.

Patented Dec. 10, 1907.

Application filed March 5, 1907. Serial No. 360,632.

To all whom it may concern:

Be it known that I, JACOB O. FUNKHOUSER, a citizen of the United States, residing at Hagerstown, in the county of Washington and State of Maryland, have invented certain new and useful Improvements in Combination Stop-Actions, of which the following is a specification.

This invention relates to that type of adjustable combination actions for organs, by which the organist, by a preadjustment or manipulation of the stop actuating mechanism at the console, can, by a single movement, bring simultaneously into effect any set or combination of stops desired and previously selected, while at the same time all of the other stops are drawn in or remain in unchanged position; in which the operating mechanism visibly affects the manually actuated parts when the various combinations are brought into play or effect so that the organist may always see at a glance what combination is "on"; and in which all of the stops may be individually actuated in the usual way, excepting at the time the adjustable combination mechanism is operating.

The invention also relates to that type of stop actions for organs in which the manual stop actuating parts are in the form of a bank of keys or levers arranged in such suitable juxtaposition to the manuals of the organ that the organist may manually draw on or draw off any one or more stops by depressing said keys of the stop action.

The primary object of my present invention is an adjustable combination action for organs which combines these two types of mechanisms before recited in an effective, simple, and durable manner, and the invention also has for its object the combination of an adjustable combination action of these types which is combined with or may be readily incorporated in a pipe organ of the tubular pneumatic type.

With these and other objects in view as will more fully appear as the description proceeds, the invention consists in certain constructions, arrangements, and combinations of the parts that I shall now herein-after specifically describe and then point out the novel features and combinations thereof in the appended claims.

For a full understanding of the invention, reference is to be had to the following de-

scription and accompanying drawings in 55 which latter:

Figure 1 is a side elevation, with parts in section, of my improved adjustable combination action; Fig. 2 is a top plan view, with parts broken away, of a bank of keys forming parts of the invention; Fig. 3 is a fragmentary perspective view illustrating one of the fans, a trip shoe set in position for actuation by said fan and other concomitant parts hereinafter specifically referred to; Figs. 4 60 and 5 are detail sectional views with parts in side elevation, illustrating two stop rods at different positions for "actuation" and "release" of the stops; Fig. 6 is a transverse sectional view with parts in side elevation, the 65 section being taken on the line x—x of Fig. 1, and looking in the direction of the dart; and, Fig. 7 is a detail perspective view, illustrating a portion of the means for releasing the stops.

Corresponding and like parts are referred 75 to in the following description and indicated in all the views of the drawings by the same reference characters.

The foundation bars 1 are provided with posts 2 on which the actuating key 3 and release key 4 are mounted to rock in a vertical plane, one above the other. The actuating key 3 extends back of its fulcrum, the post 2, and at its rear end is formed with a valve or pallet 5 adapted to control the exhaust passage 6 leading from the register of stops, in the usual manner. The said key 3 is provided with a thickened front end, as indicated at 3^a, the front face of this thickened end being beveled, as shown, and adapted to 80 display the name of the stop, while the upper edge of such thickened portion is adapted, in one position of the actuating key, to lie flush with the upper surface of the release key 4 and cover the front edge thereof which is 85 preferably blackened, or of some contrasting color, so that as is customary in these cases, the depression of the front end of the actuating key 3 will display the black end of the release key and indicate to the organist that 90 that particular stop has been drawn, or is "on". A spring 7, which, in the present instance, is a leaf spring, is interposed between the foundation bar and the actuating key 3 in advance of its fulcrum, while a similar 95 spring 8 is interposed between the actuating key 3 and release key 4, said springs manifestly tending to rock said keys so that the

stop will be brought to the "off" position. A rail 9 extends across the keys, so as to limit the upward movement thereof. 10 and 11 designate front and rear guide pins 5 for the keys.

In order to automatically hold the actuating keys 3 in a rocked position so as to maintain a stop "on", each actuating key is provided with a recess 12, each release key 4 is 10 provided with a superposed recess 13, and a latch 14 is pivotally mounted on each foundation bar 1 and projects upwardly through the recess 12 and into the recess 13 and is provided with a downwardly facing hook 15 15 adapted to engage the key 3 when the same is depressed to draw "on" a stop. 16 designates a spring tending to press the latch 14 into operative position. It will be seen that the latch 14 is provided above its hook with 20 a beveled end, so that the shoulder formed at the front edge of the recess 13 will ride upon said beveled extremity and swing the latch 14 backwardly so as to disengage the latch from the key 3 when the key 4 is depressed. Hence, it will be understood that 25 any stop may be manually drawn by depressing an actuating key 3 and be changed to the "off" position by depressing the release key 4 of that particular stop.

30 All of the above refer solely to the manual adjustment of the various stops of the action, which in itself forms no part of my present invention, and I shall now describe the adjustable combination features in which my 35 invention resides and which are combined with, or correlated to the manually actuated parts, as will hereinafter be fully shown.

Each actuating key 3 is provided at its rear end with an upwardly projecting stirrup 40 17 in which the reduced lower end 18^a of a stop bar 18 is received and pivotally connected. The stop bars 18 are, in the present instance, arranged for vertical movement and may be guided at their upper ends by 45 passing freely through apertures in the top 19 of the casing of the action, or by any other suitable means. To each one of the stop bars is secured one or more tilting trip shoes 20, the number of shoes on each bar depending upon the number of combinations that 50 may be brought successively into effect, and the said shoes for the same combination, are arranged in transversely extending series so that those on each bar lie alongside of the 55 corresponding shoes of the same series on all the other bars, when said bars occupy the same relative vertical or longitudinal positions. The several trip shoes of each bar are located one above the other, as shown.

60 Each trip shoe 20 is pivoted to the side of a bar and is provided with a spring 21 adapted to bear frictionally thereagainst so that the shoe will be held at any position to which it is swung or tilted, and the tilting motion of said shoes is limited by means of pins 22, in

an evident manner. Each tilting trip shoe 20 embodies a leg 23 extending from its pivot in one direction, a heel 24 extending rearwardly on the opposite side of the pivot, and a forwardly projecting toe 25 that is adapted 70 to be brought within the plane of the front edge of the stop bar, as indicated in Fig. 5, or to be swung out so as to project beyond such edge as indicated in Fig. 4.

In order to set the trip shoes 20, I provide 75 a setter device, one for each series of shoes, and accordingly, therefore, one for each mechanically-operated combination of which the action is capable. In the present instance, I have shown, for the purpose of illustration only, two combinations, I provide two setter devices, that for combination "No. 1" being designated A and that for combination "No. 2" being designated B. Each of these setter devices embodies a transversely 80 extending setter bar which is secured at its ends to the fingers 26 mounted upon a transverse axis or spindle 27, so that as said axis is turned, the setter bar will have an oscillating motion imparted to it towards and from the 85 trip shoes of a series. In the normal inoperative position, each of the setter bars is supported by a rest rail 28. These setter bars may be actuated at the console in any preferred manner, and for the purpose of illustration only, I have here selected and shown axes 27 provided with cranks 26 to which 90 pull rods 30 are connected. These pull rods may extend forwardly and be moved by the ordinary draw knobs (not shown).

95 The setter bars are designed to be swung against either the heel or leg of all the trip shoes of the same transverse series to tilt said shoes one way or the other, all depending upon the vertical position of the respective 100 stop bars 18 at the time the setter bars are actuated, and this in turn depending upon which of the keys 3 is depressed or raised at its front end to bring a stop "on" or "off", at the time said setter bars are actuated. 110

This advance setting of the trip shoes to either one or the other of these two positions, that is, with the toe portion 25 projecting beyond the front edge of the stop bar or lying within the plane of such edge as indicated in 115 Figs. 4 and 5, determines the performance of the various stop-bars when they are subsequently acted on by the mechanism that brings the several combinations into effect. This mechanism comprises fans C and D, one 120 for each mechanically operated combination, said fans extending transversely as shown and adapted to oscillate across the planes of the toe portions of the tilting trip shoes 20. Each fan is carried by fingers 31 secured to a 125 transversely extending axis or spindle 32 which may be turned in any preferred way. In the present instance I have shown each spindle 32 provided with a crank arm 33 to which a pull wire or rod 34 is connected, said 130

wires being controlled by a treadle, draw knob, or piston actuated by a pneumatic or electric motor (not shown). When a fan is thus actuated, it will be brought against the toe portions of those shoes that have been tilted so as to project beyond the stop bars and thereupon raise those bars that have been set to be raised, but will not affect the other bars.

10 From the foregoing description in connection with the accompanying drawings, it is evident that the organist, by depressing those actuating keys 3 for the stops which he desires to be brought "on" at a predetermined time, 15 and then actuating the setter bars, may bring the shoes of the desired stops out into the path of movement of the fans, and may then at the desired time and by a single operation of the draw knob, piston, or the like, draw all 20 the stops which he has thus previously selected, no matter how such stops have been up to this time manually drawn or retracted. But it will be seen that it is also essential for those stops that are not desired in the mechanically 25 operated combination, to be released or drawn "off" at the same time the desired stops are drawn "on", and to effect this result, I employ the following mechanism.

An unlatching bar 35 extends transversely 30 underneath the keys 3 and is mounted to reciprocate in a horizontal plane within slots in guide plates 36. This unlatching bar 35 is secured to releasing rods 37 that extend rearwardly and are in turn secured to depending crank arms 38 on a transversely extending shaft 39. In addition to the crank arms 38, the shaft 39 is provided with a rearwardly extending crank arm 40 preferably located about midway of the mechanism, 40 and provided with a laterally extending pin 41 at its free end. This pin is designed for engagement by an upwardly and forwardly facing hook 42 formed on the lower free end of the pivoted finger 43 which has a jointed 45 connection with its vertically extending release bar 44. The said arm is provided with a slot 45 for each mechanically operated combination of which the mechanism is capable, and each of the fans is provided with a pin 46 having play within one of the slots 45, as clearly illustrated in Figs. 1 and 3. The jointed finger 43 of the release bar 44 is provided with a cam slot 47 through which a rod 48 extends, the said rod being stationary and 50 supported in any desired way, and the finger 43 is under tension at all times, so as to cause the engagement of the cam surface 47 with the rod 48 as well as the engagement of the hook 42 with the pin 41, through the instrumentality of a compression spring 49 which is secured to said finger and to a rail 50. By reason of the connection between the fans C and D, it is evident that the release bar 44 will be raised at every actuation of a fan to 55 bring on the desired combination. As a fan

is swung upwardly, the first action of the bar 44 in its rising movement will be to rock the shaft 39, owing to the engagement of the hook 42 with the pin 41 and this will result in drawing the unlatching bar 35 rearwardly 70 against all of the latches 14 and effect the release of all the actuating keys. The continued upward movement of the bar 44 will result in the finger 43 riding with its cam surface 47 on the rod 48 and this will obviously 75 rock the finger 43 rearwardly so as to disengage the hook 42 from the pin 41 and allow the spring shaft 39 to rock backwardly again under the influence of the spring pressed latches 14 so as to permit said latches to assume an operative position where they will engage with and hold down those actuating keys 3 that have been previously set, when such set keys are actuated by means of the engagement of a fan with the projecting toes 80 25 of the trip shoes. To those skilled in this art, it is clear that this momentary release of all of the keys by the unlatching bar 35 is essential, so that those keys that are not desired at the time the combination is brought 90 "on" may be swung upwardly by their springs 7 and withdraw the stops which they govern. It is also clear that this releasing movement of the latches should be momentary only, so that the latches may be left in 95 position to engage the subsequently moved actuating keys 3 of the stops that are to be drawn by the combination mechanism. And it is also clear that the mechanism should operate in the following sequence; 100 first, a release of all the keys; second, a release of the latches so as to permit them to become operative again; and, third, the engagement by the fans, of those stop bars that have been set. It will be noted that 105 my arrangement of parts clearly fulfills all of these requirements.

In describing briefly the full operation of my improved adjustable combination action, reference is to be had particularly to 110 Figs. 1, 4 and 5. The position of parts as shown in Fig. 1 indicates that the key has been manually depressed at its outer end so as to raise it at its rear end and elevate the stop bar 18 and the setter bar A has then been oscillated to trip the lowermost shoe 20 to the "on" position, so that such stop will speak when combination "No. 1" is drawn. The release key has then been actuated to effect the lowering of the stop bar 18 and 115 setter bar B has been oscillated to swing the uppermost shoe 20 where it will not be affected by the fan D when the combination "No. 2" is brought into operation. Then with the parts in this position, the organist having determined that the stop shown shall be brought "on" or shall speak in combination "No. 1" and be silent in combination "No. 2", he is free to draw or withdraw the 120 said stop during the playing of the selection 125 130

until he desires the previously selected combinations, at which time, he will first actuate fan C for combination "No. 1." The actuation of this fan will manifestly raise the bar 5 18 and rock the lever or actuating key 3 so as to cause its engagement with its latch 15 and the consequent speaking of the stop during all the time combination "No. 1" is in effect. Between the time combination "No. 1" is 10 brought into effect and the time it is desired to bring on combination "No. 2", the organist is again free to actuate the key 3 to either the "on" or "off" position as often as he pleases. When, however, combination "No. 15 2" is desired, the fan D will be actuated and in its actuation will merely raise the release bar 44 which in turn will release the key 3 and permit the said key to either rock back to its closed or "off" position, if it happens 20 to be "on" at the time, or will manifestly not affect such key, if it happens to be "off" at the time.

It will, therefore, be seen that I have provided an adjustable combination action for 25 organs of the key lever type so that the organist, by preadjustment of the stop keys at the console can by a single movement, bring simultaneously into effect any combination of stops desired and previously selected, 30 while at the same time all of the other stops that are "off" when the combination is brought "on" remain untouched and those that are "on", but are not desired when the combination is brought "on" are withdrawn. 35 It will also be seen that the mechanically operating parts visibly affect the stop actuating keys at the console so that the organist may see at a glance what combination is "on", and that each and every stop may be individually actuated in the usual way, except at 40 the time the adjustable combination mechanism is operating. A proper amount of lost motion or play is permitted between the respective fans C and D, and the releasing bar 45 44, so that the movement of one fan will not interfere with the proper movement of the other.

While, I have herein shown the bank of 50 keys of my improved adjustable combination action as embodying five actuating and releasing keys, each of which is capable of inclusion in, or exclusion from two combinations, it is to be understood that my invention is not limited to this number of keys or 55 number of combinations.

Having thus described the invention, what is claimed as new is:

1. A stop action for organs, comprising a 55 60 manually operable stop actuating key, means for engaging said key to hold the stop "on", means for mechanically moving said key to the "on" position, and means for momentarily releasing the key holding mechanism before the completion of such mechanical 65 movement.

2. A stop action for organs, comprising a manually operable stop actuating key, means for mechanically moving said key to the "on" position, a latch adapted to automatically engage and hold said key in such position, 70 and means engaging said latch, for automatically releasing the same before the completion of the mechanically actuated movement of said key to the "on" position.

3. A stop action for organs, comprising a 75 manually operable stop actuating key, a stop bar operatively connected thereto, a tilting trip shoe mounted on said stop bar, means adapted to swing across the plane of said trip shoe in the direction of movement of the stop 80 bar, the trip shoe being tiltable so as to project into the path of movement of said last named means, or be retracted out of the way of such means, whereby when projected, the actuation of such means will move the stop 85 bar and also move the stop actuating key to the "on" position, means for holding said key in the "on" position, and means for tilting said trip shoe.

4. A stop action for organs, comprising a 90 stop actuating key fulcrumed intermediate of its ends, a stop bar connected to the rear end of said key, an operating trip shoe mounted on said stop bar and adapted to be projected beyond one edge thereof, a fan 95 arranged to swing into engagement with the projecting end of the trip shoe whereby to move the stop bar, means for setting said trip shoe, a latch adapted to automatically engage with the key and hold it in the "on" 100 position, and means actuated by said fan for momentarily releasing the latch.

5. A stop action for organs, comprising a 105 manually operable stop actuating key, an automatic latch adapted to engage and hold said key in the "on" position, mechanical means for moving said key to the "on" position, and means actuated by said mechanical means for automatically releasing said latch previous to the movement of said key 110 by the said mechanical means.

6. A stop action for organs, comprising the combination of a manually operable stop actuating key, a stop bar connected thereto and movable in one direction to move said key to the "on" position, means for automatically returning the key to the "off" position, a trip shoe pivotally mounted on said bar and provided with a toe, setter mechanism movable for engagement with said shoe 115 on opposite sides of the pivot thereof, whereby said setter mechanism will move the shoe in one direction or the other according to the location of said shoe with respect to the setter mechanism, a fan movable in the same 120 general direction as the stop bar, the movement of said fan being in the path of the toe of the shoe, when projected, and means for actuating said fan.

7. A stop action for organs, comprising a 130

- bank of manually operable stop actuating keys, means for automatically engaging and holding the respective keys in an "on" position, mechanical means for moving any one or more previously selected keys to the "on" position, and means for moving the remaining keys to the "off" position before the completion of the movement of the other keys to the "on" position.
10. 8. A stop action for organs, comprising a bank of manually operable stop actuating keys, mechanical means for moving any one or more of said keys previously selected, to the "on" position, means for automatically holding said keys in said "on" position, and means for moving the remaining keys to the "off" position before the completion of the movement of the other keys to the "on" position.
15. 9. A stop action for organs, comprising a bank of manually operable stop actuating keys, means for automatically holding the respective keys in the "on" position, mechanical means for moving any one or more previously selected keys to the "on" position, and means actuated by said mechanical means for releasing the key-holding means of the remaining keys.
20. 10. A stop action for organs, comprising a bank of manual stop actuating keys, a series of latches adapted to engage the respective keys when moved to the "on" position, mechanical means for moving any one or more previously selected keys to the "on" position, and means for moving all of said latches to the released position momentarily, during the operation of said mechanical means.
25. 11. A combination stop action for organs, comprising a bank of manually operable stop actuating keys, a series of latches adapted to automatically move into engagement with the respective keys in the "on" position, mechanical means for moving any one or more previously selected keys to the "on" position, means actuated by said mechanical means for automatically moving said latches to the released position, and means for moving said latches back to their operative or normal position during the mechanical actuation of the said selected keys to the "on" position.
30. 12. A stop action for organs, comprising a bank of manually operable stop actuating keys, latches adapted to hold said keys in the "on" position, mechanical means for moving any one or more previously selected keys to the "on" position, an unlatching bar arranged for engagement with all of said latches and adapted to move them to the released position, an operative connection between said unlatching bar and the mechanical means for actuating said keys, and means for automatically breaking such connection during the movement of said mechanical means in its actuation of said keys.
35. 13. A stop action for organs, comprising a manually operable stop actuating key, a spring latch adapted to hold said key when in the "on" position, means including a fan for moving said key to the "on" position, an unlatching bar adapted to move the latch to the released position, a connection between said unlatching bar and said fan, whereby the latter will actuate the former, and means for breaking such connection during the movement of said fan in the actuation of said key.
40. 14. A stop action for organs, comprising a manually operable stop actuating key, a spring pressed latch adapted to hold said key in an "on" position, a stop bar connected to said key, a fan adapted to move said stop bar, an unlatching bar arranged for engagement with the latch so as to move the latter out of engagement with the key, a releasing bar operatively connected to said fan and movable thereby, a connection between said releasing bar and said unlatching bar, and means for automatically breaking such connection.
45. 15. A stop action for organs, comprising a manually operable stop actuating key, a spring pressed latch adapted to hold said key in an "on" position, a stop bar connected to said key, a fan adapted to move said stop bar to move the key to the "on" position, an unlatching bar arranged for engagement with said latch and adapted to move the latter out of engagement with the key, a crank shaft operatively connected to said bar, the crank arm of said shaft being provided with a pin, a releasing bar operatively connected to said fan and movable thereby, said bar being provided with a jointed finger having a hooked extremity spring pressed into engagement with said pin, said finger being also formed with a cam surface, and a rod engaging said surface and adapted to move the hook out of engagement with said pin, as and for the purpose set forth.
50. 16. A combination stop action for organs, comprising a manually operable stop actuating key, a spring pressed latch adapted to hold said key in an "on" position, a stop bar connected to said key, a plurality of fans movable one independently of the other and adapted to actuate said stop bar, an unlatching bar adapted to throw said latch out of engagement with the key, a release bar adapted to actuate said unlatching bar and having an operative connection with said fans, said connection providing for a limited amount of play between each of said fans and the release bar.
55. 17. A combination stop action for organs comprising a bank of manually operable stop actuating keys, means for automatically en-

gaging and holding the respective keys in an "on" position, mechanical means for moving any one or more selected keys to the "on" position, and means for moving the 5 remaining keys to the "off" position.

18. A combination stop action for organs, comprising a bank of manually operable stop actuating keys, mechanical means for moving any one or more of said keys to the

"on" position, and means for automatically holding said keys in the "on" position.

In testimony whereof I affix my signature in presence of two witnesses.
